UNITED STATES PATENT OFFICE.

MAURICE BOXER, OF SAN FRANCISCO, CALIFORNIA, ASSIGNOR TO BEAUTY PARLOR DESIGNATOR MANUFACTURING CORPORATION, OF SAN FRANCISCO, CALIFORNIA, A CORPORATION OF CALIFORNIA.

DISPLAY DEVICE.

Application filed August 31, 1925. Serial No. 53,737.

My invention relates to display or advertising devices and one of the objects of the invention is to provide a novel and attractive display figure upon which various coiffures may be arranged so that the different styles of hair dressing may be illustrated and compared.

My invention possesses other objects and features of advantage some of which with the foregoing will be set forth in the following description of the preferred form of my invention which is illustrated in the drawings accompanying and forming part of the specification. It is to be understood that I do not limit myself to the showing made by said drawings and description, as I may adopt variations of the preferred form within the scope of my invention as set forth in the claims.

Referring to the drawings: Figure 1 is an elevation, mostly in vertical section, of my complete display device. Portions are omitted to reduce the length of the figure. Figures 2 and 3 are perspective views showing the chief feature of my display device from different view points.

In terms of broad inclusion the display device of my invention comprises a housing, the central portion of which is transparent, and in the transparent portion of which is arranged a display figure comprising a base preferably of ornamental character, and from which project two simulated human heads, joined in such a way as to leave the face and side of each head free. The heads are preferably those of beautiful women, and on each head is modeled or otherwise displayed a distinctive coiffure. Preferably I display a half-coiffure on each side of each head so that each head displays two different styles of head-dress.

In order to avoid the appearance of a monstrosity, it is necessary to effect the junction of the two heads, and the arrangement of the coiffure with extreme care. Only after repeated experiments, was the arrangement shown in the drawings finally evolved, it being found that the juncture of the two heads had to be effected along an area extending vertically behind corresponding ears of the heads. In order that the display figure may be seen to best advantage I arrange it upon a turn-table and provide

means for slowly rotating the turn-table, so that the observer can study and compare the different coiffures and reach a conclusion as to which one is best suited to herself.

In detail my invention comprises a base 2 of ornamental character, as shown in the drawings; and preferably artistic figures 3, in bas-relief, appears above the lower portion thereof. Extending above the upper portion of the base are the two heads 4 and 5 which simulate the heads and faces of beautiful women. These heads merge together along an area extending vertically just behind the right ear of each of the heads; and the left shoulder of one merges into the right shoulder of the other. The merging of the shoulders is hidden by the strands of hair fixed on the right side of each head and extending downwardly below the ear and over the merged shoulders.

For example, in Figure 1 strands of hair 7, on the head 5, extend downwardly from the part line 8, over the ear, and merged shoulders. This illustrates one style in which the hair may be dressed.

In Fig. 3, the same hair 7, is shown from another view-point. On the opposite side of the same head, another hair dress or coiffure 9 extends from the part line 8 and illustrates another mode of dressing the hair.

On the right side of the head 4, the almost straight hair 11 extends from the part line 12 over the ear of the head and across the merged shoulders of the figures as shown in Fig. 2. This particular style of dressing the hair is different than the other two already explained. On the opposite side of the head 4, the hair 13 is shown bobbed.

The figures thus display four different styles of dressing the hair and by reason of their arrangement and close proximity, these styles may be studied and compared much more effectively than upon separate figures.

Means are provided for mounting the base carrying the coiffures, and for slowly rotating the mounting, so that the figure slowly revolves before the observer. It gives the observer opportunity to see all sides of the various hair dresses and judge of their respective effects from all angles.

Mounted in the head 21 of the pedestal 22 is a plate 23, upon which the motor 24 is mounted, and connected by any suitable

electrical conductors to a source of energy. Arranged on the motor frame is a frame 26, in which is journaled in suitable bearings, the vertical shaft 27, on the upper end 5 of which, is disposed the plate or turn-table 28.

At the lower end, the shaft 27 is provided with a worm wheel 29, which is driven by the worm 31, on the same shaft with the pulley 32. This pulley and the pulley 33 on the motor shaft, are connected by a belt 34, so that with rotation of the motor, the shaft 27 is driven continuously at a much reduced rate of speed. The plate or turn-table 28 15 with its display figure is therefore rotated slowly before the observer.

It is desirable to supplement the information contained by the display figures with pictures or advertising matter, and means 20 are provided for presenting this in an attractive way. Journaled loosely on the shaft 27 and bearing on the top of the frame 26 is a collar 36 having the radially extending flange or spider 37 upon which is arranged a drum 38. Plaques 39, showing pictures or advertising matter as desired, are mounted on the drum 38, and preferably there are six of such plaques. Interposed 25 between the collar 36, and the shaft 41 journaled in the top of the frame 26, is a Geneva gear, 42 or similar mechanism for transmitting intermittent motion from the shaft 41 to the collar 36 and the connected drum 38.

35 Preferably the Geneva gear is so arranged that with six revolutions of the shaft 41 there is but one revolution of the collar 36 and drum 38. Shaft 41 is driven by a gear 43, fixed thereon and meshed with 40 a gear 44, fixed on the shaft 27. The result of this structure is that while the shaft 27 and display figure are rotated slowly, the drum 38 with its pictures or advertising matter is being moved intermittently, the 45 pauses being for a period long enough to permit easy reading of the advertising and examination of the pictures. From any one viewpoint all six faces of the drum are seen during one complete revolution.

50 Surrounding the drum 38 and supported on the upper edge 46 of the pedestal is a housing in which transparent windows 47 alternate with vertical sash members 48. The arrangement of the windows 47 and the mechanism for driving the shaft 27 and drum, is such that the drum comes to rest 55 with the display panels in register with

the windows, so that in any one window the various panels are successively displayed.

The vertical sash members 48 form the 60 division bars between the windows, and also provide support for the ring 51, upon which is arranged the housing 52, formed of plate glass or glass in tubular form. The housing 52 is transparent so that an unobstructed 65 view of the display figure is provided, and as a finish, the housing is surmounted by the top 53.

The display figure of my invention is of great importance in the so-called beauty parlors, and greatly facilitates the selection 70 of a becoming hair-dress. It also constitutes a valuable, novel and interesting exhibit.

75 I claim:

1. A display figure comprising the simulation of two human heads merging together along an area extending vertically just behind corresponding ears of the heads, and coiffures illustrating a plurality of head 80 dresses arranged on the respective heads.

2. A display figure comprising the simulation of two human heads merging together along an area extending vertically just behind corresponding ears of the heads, and a part-coiffure arranged on each side of each 85 head, each part-coiffure being different from the other, whereby different head dresses are displayed for study and comparison.

3. A display figure comprising a base, a 90 projection from said base simulating two human heads merging together, coiffures illustrating different head dresses arranged on the respective heads, means for supporting said base, and means for rotating said 95 supporting means.

4. A display figure comprising a base, a projection from said base simulating two human heads merging together, coiffures illustrating different head dresses arranged 100 on the respective heads, a plate on which said base is supported, and means for slowly rotating said plate.

5. A display figure comprising a base, a projection from said base simulating two 105 human heads merging together, coiffures illustrating different head dresses arranged on the respective heads, means for supporting said base, means for rotating said supporting means, and a transparent housing 110 about said base and heads.

In testimony whereof, I have hereunto set my hand.

MAURICE BOXER.
